Sol. H. Bellamy

United States Patent Office.

JOHN H. BELLAMY, OF CHARLESTOWN, MASSACHUSETTS.

Design No. 4,268, dated August 2, 1870.

DESIGN FOR A BRACKET.

The Schedule referred to in these Letters Patent and making part of the same

To all whom it may concern:

Be it known that I, JOHN H. BELLAMY, of Charlestown, in the county of Middlesex and State of Massachusetts, have invented and produced a new and original Design for a Bracket, of which the following is a full, clear, and exact description, reference being had to the accompanying photograph making part of this specification.

This invention consists in a bracket having emblems and scroll-work arranged and grouped together so as to produce an ornamental and unique open-work design.

In the photograph—

A represents the shelf which rests upon the ornamental open-work support B.

The back C is of ornamental scroll-work, and that portion above the shelf A incloses three links D D D, arranged in the arc of a circle, within which are seven stars, E, together with a half-moon, G.

On the right-hand side of the links D is a bundle of rods, H, and on the left-hand side a budded rod, I. Surmounting the links D, and connected with the central one, is an open hand, K, in the center of which is a heart.

Claim.

What I claim as my invention, and desire to secure by Letters Patent, is—

The design for a bracket, herein shown and described.

Witness my hand this 11th day of July, A. D., 1870.

JOHN H. BELLAMY.

Witnesses:

P. E. TESCHEMACHER,
W. J. CAMBRIDGE.
